Y. SHIBA

WATCH CHAIN FASTENER

Filed July 25, 1925

INVENTOR
Y. SHIBA

BY *Chas. Schum*
ATTY.

UNITED STATES PATENT OFFICE.

YAICHIRO SHIBA, OF SAN JOSE, CALIFORNIA.

WATCH-CHAIN FASTENER.

Application filed July 25, 1925. Serial No. 45,961.

To all whom it may concern:

Be it known that I, YAICHIRO SHIBA, a subject of the Emperor of Japan, residing at San Jose, in the county of Santa Clara, State of California, have invented new and useful Improvements in Watch-Chain Fasteners, of which the following is a specification.

This invention relates to a novel and convenient means for locking a vest pocket or other type of watch chain so that said chain and watch will be safeguarded against theft and the watch and chain prevented from falling from the wearer to which it is attached.

An object of the invention is to provide a simple and inexpensive clasp which is adapted to lock over and on one of the buttons of a vest and which is carried by a watch chain, said clasp not only serving to effectively lock the chain in place and making it unnecessary to insert the chain through the button-hole as is the common practice, but serving as an ornament as well.

Another object of the invention is to provide a watch chain locking device of the character described which may be incorporated with a chain as a link thereof and which may be quickly and easily placed and locked upon and removed from a vest button.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a top plan view of the lock of the invention showing a part of the chain with which it is incorporated and the lock in position as when locked on a button, which latter is shown in dotted lines.

Fig. 2 represents a vertical sectional view taken through the lock.

Fig. 3 represents a top plan view of a slightly modified form of lock, shown on a button, illustrated in dotted lines.

Fig. 4 represents a vertical sectional view of the lock shown in Fig. 3.

Fig. 5 represents a top plan view of the form of lock shown in Fig. 3 illustrating the manner of attaching the lock to a button.

Fig. 6 represents a vertical sectional view of the form of lock shown in Figs. 3, 4 and 5, the lock being in open position.

Fig. 7 represents a front elevation of the lock and chain showing it as it would appear when in use attached to the vest of the wearer.

The lock of this invention comprises a disk or plate-like body portion 1, in the present instance of circular form, provided on opposite sides with eyes 2 and 3 to which the sections 4 and 5 are attached. The chain shown more particularly in Fig. 7 is of the type to be worn in vest pockets although the lock of the invention may be used with other styles of chain. The body portion 1 is provided with a bifurcated clasp 6 on the rear face thereof, which clasp is formed integral with the flange 7 extending part way of the circumference of the body. The terminals of the clasp are enlarged and rounded as at 8 so that ready and easy attachment of the lock may be effected and the enlarged end will provide for an effective clamping or locking action.

To attach the lock, the bifurcated clasp 6 is slipped behind the button so that the body portion 1 will extend over and conceal the button. The flange 7 is curved in cross section so that it will extend over the rear face of the button and thereby assist in holding the lock on the button. The outer face of the body plate of the lock may be decorated as desired to make the lock ornamental as well as useful.

With the lock in place as shown in Fig. 7, it is unnecessary to insert the chain through the button-hole as is the common practice, and not only is the chain and watch or other device attached to the chain, such as a knife, trinket or charm, safeguarded against theft but should the wearer stoop over, the chain with the articles attached thereto will not drop off of the vest even though the watch and articles on the other end of the chain might fall from the pockets. The device may be quickly and easily placed upon and removed from the button but is securely held against accidental displace-

ment. Some force is required to remove the lock from the button so that the wearer will readily detect an unauthorized operation of removing the lock.

- 5 In Figs. 3 and 6 inclusive, the modified form of lock comprises a circular disk-like body portion 9 having eyes 10 and 11 on opposite sides, to which eyes the sections 12 of the chain are attached. The body portion 10 of this lock is provided with a curved flange 13 extending substantially half way around the periphery of the body. Pivoted centrally as at 14 on the rear face of the body 9, is a circular locking disk 15 having a segmental pocket 16 which, together with the flange 13, provides for completely encompassing a vest button so that it is impossible to remove the lock without turning the body 9 and disk 15 relative to one another.
- 10 As shown in Fig. 5 the locking disk 15 with the pocket 16 is moved into position in registration with the flange 13 so that the lock may be slipped over a button. Following the movement of the lock over a button 15 so that half of the button extends into the pocket 16, the disk 15 is turned to bring the pocket so as to receive the opposite side of the button to that received in the curved flange 13 and the lock and chain are securely held on the button. To remove the lock, it is only necessary to grasp the chain adjacent the eyes and move the eyes downward and the button may be slipped out of the pocket 16.

The device of this invention may be incorporated with any style of link chain in the same manner as a link is attached to a chain, it being preferably attached centrally of the ends of the chain. The lock is small and may be easily and cheaply made. If desired the outer face of the lock may be decorated so that the lock will serve as a watch charm or ornament.

I claim:

1. A lock for watch chains comprising a circular body member adapted to be extended over the front of a vest button, which member is provided with eyes on opposite sides so that it may be incorporated with a watch chain between the ends of the latter, a flange extending rearwardly from the outer edge of the body, being curved in cross section so as to extend behind the button and means on the back of the body for clasping the body to a button.

2. A lock for watch chains comprising a circular body member adapted to be extended over the front of a vest button, which member is provided with eyes on opposite sides so that it may be incorporated with a watch chain between the ends of the latter, being curved in cross section so as to extend behind the button and means on the back of the body for clasping the body to a button, which means comprises a disk rotatably mounted on the body having a segmental button receiving cut therein adapted to receive a button.

YAICHIRO SHIBA.
